UNITED STATES PATENT OFFICE

2,502,274

ATTACHMENT FOR LATHE MACHINES

Robert O. Pearce, Elgin, and Robert W. Kramer,
Carpentersville, Ill.

Application June 12, 1947, Serial No. 754,224

9 Claims. (CL 82—36)

This invention relates to new and useful improvements in attachments for lathe machines and the primary object of the present invention is to provide a carrier supporting a tool that engages a piece of work for machining the same and said carrier includes means whereby the tool is retracted from engagement with the master screw or work as the carrier contacts a carrier stop mounted on the lathe.

Another important object of the present invention is the provision of an attachment pivotally mounted on a lathe bed and supporting tools at each end thereof for selective movement into engagement with a piece of work that is rotated by said lathe machine.

A further object of the present invention is to provide a tool carrier including novel and improved means for advancing and retracting said carrier relative to a piece of work.

A still further aim of the present invention is to provide a lathe attachment that is simple and practical in construction, efficient and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part thereof, wherein like numerals refer to like parts throughout, and in which:

Figure 1 is a side elevational view of the present invention, with parts broken away and shown in section;

Figure 2 is a top plan view of Figure 1;

Figure 3 is a transverse vertical sectional view taken on line 3—3 of Figure 1;

Figure 4 is a longitudinal vertical sectional view taken on line 4—4 of Figure 2;

Figure 5 is an enlarged fragmentary horizontal sectional view taken on line 5—5 of Figure 1, and with parts broken away and shown in section; and,

Figure 6 is a fragmentary perspective view of the advancing and retracting mechanism for the tool carrier.

Referring now to the drawings in detail, wherein for the purpose of illustration, there is disclosed a preferred embodiment of the present invention, the numeral 10 represents the tool holder or lathe attachment generally comprising a base or anchor member 12 that is pivotally mounted by fastening member 14 to a lathe machine bed (not shown) or any other similar type of machine.

Base member 12 is provided with a cut out por-

tion having longitudinal channels or grooves 18 and 20 formed in its respective lower face 22 and upper face 24.

A substantially rectangular carrier 26 is provided with longitudinal ribs or projections 30 and 32 at its lower face and upper face respectively that engage channels 18 and 20.

Inclined tool receiving bores or apertures 34 are provided in the carrier 26 at each end thereof and engage the shank portions of tool 36 adjustable in the apertures by fastening members 38.

The carrier 26 is provided with a central substantially rectangular cut out portion 40 divided into two equal chambers 42 by a removable stop member 44 having a reduced inner portion 46 that frictionally engages an aperture 48 centrally disposed in the inner face 49 of the base member 12.

Coil springs or the like 50 are frictionally retained in each of the chambers 42 and are biased between the stop member 44 and the opposing vertical side faces of the chambers.

The upper forward portion 52 of the member 12 is covered by a lid or top plate 54 that is removably secured to said portion 52 by fastening means 56. Both the upper plate 54 and upper portion 52 are provided with a central cut out portion 58, in which is mounted a locking pin 60 having a rib 62 formed at its lower face, that bears on the rib 32 at the upper face of the carrier.

An arcuate spring arm 64 is secured at its center to pin 60 and its ends normally bear against the inner face of the upper plate, for urging the rib 62 of the locking pin 60 against rib 32.

Extending transversely through the upper portion 52 at each end thereof, and at right angles to rib 32, are apertures 66 in which are slidably mounted preferably rectangular actuating bars 68 and 70 each having a substantially V-shaped notch 72 at their opposite ends that engage the terminal portions of a rockable lever bar 74 carried by the locking pin 60.

The inturned reduced portion 76 of an angular lever arm 78 is pivotally mounted in carrier 26 and the upstanding portion of the arm 78 is supported by sleeve 80 having a boss 82 projecting outwardly therefrom that pivotally engages an aperture provided in the upper plate, and a set screw 84 carried by the upper plate loosely engages an annular recess 86 provided in the boss. The foregoing construction, permits the rotation of boss 82 relative to the upper plate 54 however, the boss will not become disengaged therefrom during its rotary movement.

In practical use of the device, the base member 12 is mounted on the bed of a lathe machine or the like so that by pivoting the base member the tool 36 will be at right angles to the work carried by the machine.

The actuating bars 68 and 70 are mounted in the upper portion 52 so that one end of one of the bars, for example 68, projects outwardly from one side of the upper portion and the outer end of the other bar 70 projects outwardly from the opposite side of the upper portion. Spring arms 88 and 90 carried by the opposite side of the upper portion 80 aid in retaining the bars in the aforementioned position.

When the hand gripping bar 92 at the upper end of lever 78 is pulled away from the work carried by the lathe, the carrier 26 is pushed forwardly relative to the base and the rib 62 of locking pin 60 engages a notch or pin recess 94 provided in rib 32, holding the carrier in an advanced position.

The carrier and base member then travel longitudinally against the work with the longitudinally movable portion of the lathe bed and upon reaching the desired point whereby it is desired to disengage the tool 36 from the work, the forwardly disposed actuating bar, for example 68, will engage an adjustable stop (not shown) provided on the lathe at a selected point which will extend the outer end of bar 68 into the upper portion 52, whereby the lever bar 74 will disengage the notch in bar 68, rocking the lever bar 74 so that the rib 62 of the locking pin 60 disengages notch 94 and the spring 50 will return the carrier to its normal position relative to the base.

Obviously, if desired, the base member may be pivoted in a complete circle so that the tool at the other end of the carrier may engage the work with rib 62 of locking pin 60 engaging the notch or pin recess 96 in rib 32. The outer end of actuating bar 70 will then be the element engaging the stop to return the carrier to its normal position relative to the base member.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A lathe attachment comprising a base member, a tool carrier slidably mounted on said base member for longitudinal movement, a support carried by said base member, means carried by said support and connected to said carrier for moving the latter, said support including a housing, a rockable lever disposed in said housing, a locking member carried by said lever and including a rib, said carrier having a plurality of longitudinal spaced recesses for receiving said rib to retain the carrier in an outwardly adjusted position relative to said base member, means carried by said locking member normally urging the rib into locking engagement with said carrier, a slidable actuating member engageable with a stop to rock said lever and disengage said rib from a selected one of said recesses, and resilient means normally urging said carrier to its normal position relative to said base member.

its normal position relative to said base member.

2. The combination of claim 1 wherein said means carried by said locking member normally urging the rib into locking engagement with said carrier includes an arcuate spring member, said housing including an upper wall spaced parallel to said carrier, the end portions of said arcuate spring member bearing against the upper wall of said housing to urge the locking member toward said carrier.

3. The combination of claim 1 wherein said actuating member includes a bar slidably carried by said carriage and movable perpendicular to the longitudinal axis of said lever.

15 4. The combination of claim 1 wherein said actuating member includes an elongated bar slidably carried by said carrier and having a notch for receiving one end of said lever, the end of said lever received in said notch including a sloping surface, said notch including an inclined surface bearing against the sloping surface of said lever to force the lever out of engagement with said notch during sliding movement of said bar in one direction.

25 5. A lathe attachment comprising a base member, a tool carrier slidably mounted on said base member for longitudinal movement, a support carried by said base member, means carried by said support and connected to said carrier for moving the latter, said support including a housing, a rockable lever disposed in said housing, a locking member carried by said lever and including a rib, said carrier having a plurality of longitudinal spaced recesses for receiving said rib to retain the carrier in an outwardly adjusted position relative to said base member, means carried by said locking member normally urging the rib into locking engagement with said carrier, a wedge member slidably on said carrier for rocking said lever to disengage said rib from a selected one of said recesses, and resilient means normally urging said carrier to its normal position relative to said base member.

6. A lathe attachment comprising a base member, a tool carrier slidably mounted on said base member for longitudinal movement, a support carried by said base member, means carried by said support and connected to said carrier for moving the latter, said support including a housing, a rockable lever disposed in said housing, a locking member carried by said lever and including a rib, said carrier having a plurality of longitudinal spaced recesses for receiving said rib to retain the carrier in an outwardly adjusted position relative to said base member, means carried by said locking member normally urging the rib into locking engagement with said carrier, a slidable actuating member engageable with a stop to rock said lever and disengage said rib from a selected one of said recesses, said actuating member including a cam receiving said lever, and means urging said carrier to its normal position relative to said base member.

7. The combination of claim 6 wherein said last mentioned means includes a bearing plate carried by said support, a slot provided in said carrier slidably receiving said bearing plate, said slot including a vertical wall spaced from said bearing plate, and a resilient member received in said slot and biased between the vertical wall of said slot and said bearing plate.

8. The combination of claim 6 and means normally urging a portion of said actuating member outwardly of said housing.

75 9. The combination of claim 8 wherein said

means includes a spring member having one end fixed to said housing, the free end of said last mentioned spring member bearing against said actuating member.
